UNITED STATES PATENT OFFICE.

LEE STUDY, OF WASHINGTON, INDIANA.

TOOL.

Application filed November 1, 1924. Serial No. 747,353.

To all whom it may concern:

Be it known that I, LEE STUDY, a citizen of the United States, residing at Washington, in the county of Daviess and State of Indiana, have invented a new and useful 5 Tool, of which the following is a specification.

This invention relates to a tool especially designed for use in trimming the edge of a 10 lawn adjacent to a sidewalk or road surface.

An important object of the invention is to provide a device of this character formed with a guiding member which will guide the tool in its work and gauge the depth at 15 which the tool may operate to insure a straight edge being formed by the tool.

Another object of the invention is to provide means carried by the tool for receiving material cut with the tool to the end that 20 the device will remove the dirt or sod cut.

With the foregoing and other objects in view which will appear as the description proceeds, the invention resides in the combination and arrangement of parts and in the 25 details of construction hereinafter described and claimed, it being understood that changes in the precise embodiment of the invention herein disclosed may be made within the scope of what is claimed without departing from the spirit of the invention. 30

Referring to the drawing:

Figure 1 is a side elevational view of the tool.

Figure 2 is a plan view thereof.

Figure 3 is a front elevational view disclosing the use of the tool.

Referring to the drawing in detail, the device includes a relatively large blade indicated generally by the reference character 40 5 which is curved transversely in a manner to provide a relatively straight wall 6 and a sloping wall 7, the front edges of the walls 6 and 7 being beveled to provide a trimming surface so the device will cut its way through 45 the sod.

Forming a continuation of the wall 6 is a flange 8 that extends at right angles to the wall 6, the forward edge thereof being bent upon itself to provide a shoe 9 which will

act to guide the tool over the ground surface 50 and prevent the tool from being obstructed in its movements through the sod.

Formed integral with the blade is a socket member 10 designed to accommodate the forward end of the handle 11 of the tool 55 whereby the tool will be forced through the ground surface or sod.

The reference character 12 indicates a tray which is formed of sheet metal and curved so that it will retain material which 60 passes thereto from the cutting blade. Arms 13 are secured to the tray 12 and have their ends terminating in curved portions 14 formed at right angled ends 15 that are apertured to receive the bolts 16, there being 65 provided winged nuts 17 on the bolts for securing the arm 13 to the handle 11 and socket member 10.

As clearly shown by Figure 1 of the drawing, the forward end of the tray 12 lies adjacent to the rear end of the blade so that as material passes through the blade, it will be fed directly to the tray 12 which may be readily removed for dumping purposes.

In the use of the device, the blade is positioned adjacent to one edge of a walk or road surface, the flange 8 resting on the upper surface of the walk or road surface, the blade resting in such position that the straight wall 6 will engage the side surface 80 of the walk or road surface.

With the blade in this position it will be obvious that when the blade is forced or moved along the road surface, the blade will cut into the sod to trim the sod evenly, at a 85 point adjacent to the walk or road surface.

I claim:

In a device of the character described, a cutting blade, said cutting blade having a socket, a handle fitted in the socket, a tray 90 removably carried by the socket and handle member, and said tray adapted to receive material from the blade.

In testimony that I claim the foregoing as my own I have hereto affixed my signature.

LEE STUDY.
